UNITED STATES PATENT OFFICE

99,816

DESIGN FOR A COMBINED SMOKING SET AND ASH RECEPTACLE

Roman Madler, Belleville, N. J.

Application October 15, 1935, Serial No. 58,995

Term of patent 3½ years

To all whom it may concern:

Be it known that I, Roman Madler, a citizen of the Republic of Poland and a resident of Belleville, in the county of Essex, State of New Jersey, have invented a new, original, and ornamental Design for a Combined Smoking Set and Ash Receptacle, of which the following is a specification, reference being had to the accompanying drawing forming a part thereof.

Fig. 1 is a perspective view of a combined smoking set and ash receptacle, showing my new design; and

Fig. 2 is a view similar to Fig. 1, but with the cover of the ash receptacle shown in open position.

Those sides of the combined smoking set and ash receptacle which are not shown are substantially the same as the respective opposite sides illustrated in the drawing.

I claim:

The ornamental design for a combined smoking set and ash receptacle, as shown and described.

ROMAN MADLER.
